UNITED STATES PATENT OFFICE

JOHN H. DAMON, OF PLYMOUTH, MASSACHUSETTS, ASSIGNOR TO PLYMOUTH CORDAGE COMPANY, OF PLYMOUTH, MASSACHUSETTS, A CORPORATION OF MASSACHUSETTS

MECHANISM FOR SLIVER CONTROL

Application filed December 27, 1929. Serial No. 416,975.

This invention relates to improvements in mechanism for sliver control. More particularly it relates to fibre preparing machines and the like, wherein a sliver of fibre, as 5 hemp, flax or sisal, may be drawn out and so reduced to a size and uniformity suitable for binder twine, rope yarns, and kindred products. The invention introduces improvements for controlling the size of the 10 sliver, produced by the machine, so that a desired thickness thereof shall be attained and maintained automatically.

In machines of this general description, a number of bunches of fibres, eight or ten, for 15 example, may be fed, side by side, into the machine, there to undergo a drawing-out process such that the aggregate of their cross-sectional areas is reduced as desired. A common method is based upon the co-action of 20 two endless belts or chains carrying fibre-engaging pins. Both belts are generally arranged horizontally and in the same plane, one in advance of the other; and both travel in the same direction but at different speeds, 25 the leading belt, i. e. that nearer the delivery end of the machine, being the faster. The fibres are drawn, by the pins of the slower belt, and are delivered to the second belt, whose faster moving pins effect the drawing 30 or combing of the fibres so that the mass gradually is reduced and thinned prior to the compacting of the fibres into sliver form.

The bunches of fibre fed into the machine are each somewhat irregular; and when a 35 number are combined, side by side, these irregularities sometimes combine to make the aggregate extra thick or extra thin. Heretofore it has been a difficult if not an impossible task to produce slivers having uniformly 40 the predetermined desired thickness. Attempts have been made to gauge the incoming material, and to regulate the drawing action of the machine according to the varying amount of material which is being sup- 45 plied. But none such have really accomplished the desired end; and the slivers which they produce have substantial variations in thickness at intervals along the sliver.

By the present invention an increase or 50 decrease in the drawing effect of the ma-

chine on the supplied fibres is occasioned by incipient variations in the thickness of the finished sliver, above or below a predetermined desired thickness. A feature of importance is that the sliver, at the place of its 55 effect upon the control mechanism, is fully formed and compacted; and thus even slight departures from the predetermined thickness can be detected. As the fibres individually may be eight or ten feet or more in length, 60 the regions of thinness or thickness in the sliver develop slowly and, under the above conditions of gauging accurately the finished product, the incipiency of a thinness can be detected, and the drawing action of the machine changed by the automatic apparatus provided, with such instantaneous effect that the regularity of the product is much better maintained than by the old method. In connection with this there may be means for indicating the prevailing thickness of the finished sliver. It is moreover an important feature that the invention is economical to 65 make, and may be installed at small cost on the machines now in common use. 70

These objects and results may be attained, according to the invention, by employing a system of levers and connections, one of which levers is pivotally mounted above the delivery rolls of the machine, and has a projecting arm, preferably equipped with a roller, resting on the movable one of the delivery rolls. A pointer is arranged to move over an indicator scale whenever the said lever moves; and connections extending rear- 75 ward operate a change speed mechanism, to cause an increased or decreased drawing effect on the fibres. Where the control device is applied to a machine having the two belts of pins, as herein illustrated, the slower belt 80 preferably will be the one affected; but a like result may be obtained by varying the speed of the faster moving belt while the speed of the slower belt is maintained constant. 85

It is intended that the patent shall cover, 90 by suitable expression in the appended claims, whatever features of patentable novelty exist in the invention disclosed.

In the accompanying drawings:

Figure 1 is a somewhat diagrammatic side 100

elevation of a fibre preparing machine embodying features of the invention;

Figure 2 is a plan illustrating the connections for control of a variable speed mechanism;

Figure 2a is detail of the delivery rolls;

Figure 3 is a side elevation, greatly enlarged, showing the direct drive for the faster chain, and showing also the means for effecting change of speed of the slower chain; and

Figure 4 is a side elevation of the delivery end of the machine, greatly enlarged.

Referring to the drawings, Figure 1 shows a fibre preparing machine of a well known type wherein two systems of fibre-engaging pins 10, 12 are mounted respectively on endless belts 14, 16 for travel horizontally, in like planes and in like direction, over a base 18. Belt 16 is arranged in advance of belt 14 and has a greater speed of travel.

Each belt embodies two side chains 20 and cross-bars 22, which latter carry the pins 10, 12. The slower moving belt 14 has its side chains trained over sprockets 24 on shafts 26, 28, and its pins 10 are adapted to engage and draw forward a mass 30 of long fibres which may be fed into the machine through the rollers 32. The other and faster travelling belt 16 is mounted in like manner on shafts 34, 36, the latter shaft being the main drive shaft of the machine, receiving its power from any suitable source (not shown).

Thus the faster moving belt travels at constant speed. The slower belt is driven directly from shaft 36 through a variable speed device indicated generally at 38, and its speed of travel may be varied as desired. In the drawings (Figure 2) a well known variable speed transmission is illustrated, in which a constant speed shaft 40 and a variable speed shaft 42 each has a pair of cone-surfaced disks 44 mounted for the disks of each pair to be spreadable apart relatively, and to be adjustable toward each other relatively. And a V-type belt 46 is trained over the disks to transmit power from the constant speed shaft 40 to the variable speed shaft 42. Turning of screw 48, effects, through arms 50, a spreading of the disks on one shaft and a closing together of the disks on the other shaft, thereby to cause belt 46 to ride high upon the disks which stand close together, and low on the spread disks. If the belt is higher on the disks of the variable speed shaft 42 than on the other pair of disks, as herein illustrated, there will be a reduction in the speed of rotation of the variable speed shaft 42 over the constant speed shaft 40. And the amount of the reduction may be varied at will by shifting of the disks 44, relatively. A cross-belt 52 drives the constant speed shaft 40 of the transmission from the main drive shaft 36 below. And a chain

54 drives shaft 28 of the slower moving belt 14 from the variable speed shaft 42 of the transmission, through suitable reduction gearing 56.

The fibre 30, entering the machine, is engaged by the pins 10 of the slower belt and by them is drawn forward and delivered to the faster belt 16 whose pins 12 engage it.

The invention provides for attaining automatically an approximate uniformity of dimension throughout the full length of each delivered sliver, by detecting instantly each incipient variation from uniformity; and for indicating the thickness of finished sliver prevailing at every instant. For this purpose, a lever 58 is pivoted at 59 on the frame below and to one side of the usual delivery rolls 60. A second lever 62 is mounted above and a little to the rear of the delivery rolls, pivoted at one end to the frame, as at 64, and having a side-wise projecting arm 65 whose end, preferably equipped with roller 66 rests on the upper one of the delivery rolls, which roll is movable vertically to accommodate variations in the thickness of sliver. The movable end of lever 62 is connected by adjustable link 68 to lever 58 below, as at 69.

Lever 58 has its rear arm held down yieldingly by the spring 70, and this arm pulls down on the vertically extending link 68 which, through lever 62 presses down on the small detecting roller 66, riding on top of upper delivery roll 60. The sliver is laterally confined, as is usual, in a groove in the under delivery roll 60, into which fits the upper roll 60, so that every variation in volume is manifest by a change of elevation of the upper roll 60; and this movement reaches the lever 58 in magnified amplitude, due to the leverage 62. Forward of its fulcrum 59 the lever 58 carries an upstanding arm 72 at whose tip is a slot through which passes the forward end of a rod 74, with yielding connection indicated by the springs 76, which rod receives the magnified fluctuations of the top delivery roll. Rod 74 runs back over the machine and constitutes an actuating rod to swing an upstanding lever 78 which is pivoted at 80 near the variable speed transmission 38.

The lever 58 also carries, forward of its fulcrum 59, a pointer 82 which is adapted to move over a scale 84 indicating thickness of the sliver which is being delivered.

The upstanding lever 78 has sprocket chain 86 connected from its one end to the other and trained over small sprocket 88, fast on the end of screw 48 of the variable speed device 38. The actuating rod 74 is connected at 90 on the upper arm of lever 78, close to that lever's pivot, so that even small movements of the rod 74 will effect relatively large movements at the lever ends, and thus of the sprocket 88 and screw 48.

In operation, the entering fibre mass 30 is subjected to a drawing or combing by the engagement of the two systems of pins 10, 12 and thus is reduced and thinned before passing between the usual rollers 92 at the end of the fast belt. From these rolls the thinned mass travels over an apron 94 to the compressor rolls 96, and finally the fibres 31 are grouped for passage between the delivery rolls 60. Inasmuch as the sliver is completely formed and compressed between the delivery rolls 60, any variations in its thickness, even of very slight character, will cause the upper delivery roll 60 to react in a vertical direction. The sensitive roller 66 will react in a like direction; and, through the magnifying leverage 62, will actuate lever 58 to indicate the variation on scale 84; and through its connection to actuating rod 74 will swing the lever 78 and the chain 86 so as to effect a turning of screw 48 of the variable speed transmission 38. The turning of this screw 48 effects a shifting of disks 44 to change the speed of the slower moving pin belt 14. If the sliver is above a predetermined desired thickness, the pin belt 14 will be slowed down a little to cause a greater drawing and thinning of the mass of fibre. If the sliver is too thin, the belt 14 will be speeded up, and the result will be less thinning effect.

I claim as my invention:

1. In a fibre preparing machine having means for drawing and delivering the fibres in sliver form, the combination, with said means, of mechanism, applied to the sliver at the place of its delivery, being there applied to the final cross-section of the sliver as completed by the machine, and responsive to variations in its cross sectional dimensions; a control device for the drawing; and connections between said mechanism and said control device, whereby the responses of said mechanism are communicated to said device to vary the degree of drawing.
  2. In a fibre preparing machine the combination, with two systems of fibre engaging pins, cooperating at different rates of travel to draw fibre, of a movable member applied to a sliver produced by the drawing, and moved by variations in the dimension of such sliver, and connections between said member and one of the systems of travelling pins for varying the speed of travel of that system, whereby the movement of said member effects a change in the speed of travel of that system relative to the speed of travel of the other system.
  3. In a fibre preparing machine having in combination two systems of fibre engaging pins cooperating at diverse speeds to draw the fibres; a device for varying the speed of travel of one said system; a pair of delivery rolls between which the drawn fibre passes, one of them being movable relative to the other and held apart therefrom by the inter-
- vening fibre; means pressing against the movable delivery roll and adapted to move in unison with said roll; and operating connections between said means and said speed varying device for varying the speed of travel of one system, whereby movements of said means effect change of speed of travel of one of the systems of pins relative to the other system.
4. In a fibre preparing machine having a relatively slow moving belt of fibre engaging pins, a faster moving belt of pins taking fibre from the first, means for varying the speed of travel of one said belt, and delivery rolls set one above the other with the upper of them loosely movable vertically toward and from the lower of them; the combination therewith of motion amplifying mechanism resting against the upper delivery roll and actuated by its said movements; and connection between said mechanism and said speed varying means, for amplifying the effect of said movements and for actuating said means to vary the speed of travel of said one belt of pins relative to the other belt.
5. In a fibre preparing machine having a relatively slow moving belt of fibre engaging pins, a faster moving belt of pins drawing from it, means for varying the speed relation of the said belts, and delivery rolls between which the fibre passes, set one above the other with the upper roll loosely movable vertically toward and away from the lower roll; the combination therewith of a pivoted lever having one arm in position to press toward the upper delivery roll and be actuated by movements of said roll; other levers transmitting the motion; an actuating rod extending from the final lever of this series; and control mechanism, for said means for varying speed, to which the said actuating rod is connected.
6. In a fibre preparing machine having a relatively slow moving belt of fibre engaging pins, a faster moving belt of pins drawing from it, means for varying the speed relation of the said belts and delivery rolls between which the fibre passes, set one above the other with the upper roll loosely movable vertically toward and away from the lower roll; the combination therewith of a pivoted lever having one arm in position to press toward the upper delivery roll and be actuated by movements of said roll; other levers transmitting and amplifying the motion; a pointer on the final lever of the series; an indicating scale over which the pointer is arranged to move, visually indicating thickness of the sliver; an actuating rod extending from the said final lever; another lever pivoted near said means for varying speed, to which lever the said actuating rod is connected; and a chain and sprocket connection between the ends of the last mentioned lever and said means for varying speed, whereby actuators

of that lever by the rod effect change of speed of travel of one of said belts of pins.

7. In a fibre preparing machine having means for drawing and delivering the fibres in sliver form, the combination, with said means of sliver gauging mechanism, constantly bearing upon and sensitive to the cross-section of sliver which is being delivered; and means, controlled by said gauging mechanism, for varying the drawing to which the sliver material is subjected prior to reaching said gauge.

Signed at Plymouth, Massachusetts, this 20th day of December, 1929.
